UNITED STATES PATENT OFFICE.

JEREMIAH E. CHAPMAN, OF PLYMOUTH, NEW HAMPSHIRE.

BOX-BINDING MACHINERY.

SPECIFICATION forming part of Letters Patent No. 431,249, dated July 1, 1890.

Application filed October 23, 1889. Serial No. 327,953. (No model.)

To all whom it may concern:

Be it known that I, JEREMIAH E. CHAPMAN, a citizen of the United States, residing at Plymouth, in the county of Grafton and State 5 of New Hampshire, have invented certain new and useful Improvements in Box-Binding Machinery, of which the following is a specification.

This invention relates more especially to 10 forming and attaching tin fastenings or binders to butter-boxes.

The object of the invention is to provide a machine capable of cutting off pieces of tin or other metal from a strip of any width, and then 15 bending and pressing the same upon the articles to be thus fastened; and the invention consists of the novel devices fully set forth in the following specification and claims and 20 clearly illustrated in the accompanying drawings, forming an inseparable part thereof, of which—

Figure 1 represents the complete machine in front elevation, Fig. 2 being a general plan view of same. Fig. 3 is a broken elevation 25 of one side of the machine. Fig. 4 is a broken view showing a portion of the opposite side, partly in elevation and partly in section. Fig. 5 is a detached perspective view of the automatically-adjustable clamps, which receive 30 and bear upon the pieces of metal after they have been bent and carry them successively to their position under the press. Fig. 6 is an inverted plan of the rotary disk upon 35 which the adjustable clamps are mounted, showing ratchet-teeth upon its hub or journal, and its operating-crank with its hub in section, displaying a spring-pawl for engaging the ratchet-teeth of said disk. Fig. 7 is an enlarged broken sectional view of the cutting, bending, clamping, and pressing mechanism 40 as seen when in a position ready to cut and bend a piece of metal. Fig. 8 is a similar view of the same parts as when one of the pieces of metal has been cut off, bent, and carried under one of the adjustable clamps. Fig. 9 is a detached plan view of that style 45 of guide which is illustrated in cross-section in Figs. 7 and 8, into or against which the metal strip must rest while being cut off, and Fig. 10 is a plan taken on line Y Y, Fig. 7, in 50 which a modified form of block P is shown.

Similar reference-letters designate corresponding parts throughout the various views.

A is the machine-frame, provided with bearings *a* for carrying the power-driven shaft *B*, 55 bearings *a'*, carrying a counter-shaft *B'*, and bearings *a''*, carrying the shaft *B''*, having one end in connection with the shaft *B* by the bevel-gears *b' b*, respectively, and its other end in connection with the shaft *B'* by the 60 bevel-gears *b'' b'*, respectively. A rotary disk *C* is depressed in the bed portion of the frame *A* in a horizontal position, and upon its under side is a journal *c*, which passes through and below the said bed portion of the frame *A*. 65 Various means may be employed to revolve this disk, one of which is shown in the drawings, to wit: The projecting portion of the journal *c* may be provided with ratchet-teeth *c'*, as seen in Fig. 6, and upon this is mounted 70 a crank *D*, carrying a suitable spring-pawl *d* for engaging the ratchet-teeth *c'*, said crank being operated in one direction by means of a rod *D'*, connecting said crank with one end of a movable rack *E*, suitably mounted in the 75 bed portion of said frame *A* and adapted to be moved by the sectional gear *E'*, carried upon the counter-shaft *B'*, as seen in Fig. 2, and in the opposite direction by means of a suitable spring, as seen at *E''* in Fig. 3 and 80 in dotted lines, Fig. 2.

The disk *C* has a portion of its upper surface elevated, as at *C'*, and in plan view this may be square, as in Fig. 10, and upon this are mounted automatically-adjustable clamps 85 *F*, constructed and placed one upon the other in the manner seen in Fig. 5. Each of these are provided with an elongated opening *f* in their longitudinal center for the reception of the screw *G*, which passes down and is 90 threaded to an opening *c''*, provided for the purpose in said disk *C*. Studs *c''* are also provided upon the portion *C'* of said disk for guiding and retaining the said clamps in their proper position laterally, and a helical spring 95 *g*, placed upon the screw *G* in a manner to operate expansively between its head and one of said clamps *F*, will cause sufficient friction between themselves and the said disk to properly regulate their legitimate motion. 100

The part *A'* of the frame *A* partially encloses a cam or eccentric *H*, mounted upon

the front end of the shaft B, having a connecting-rod I, which is attached or pivoted to a plunger J, which presses the pieces of metal l upon the articles they are to fasten, after 5 the same has been cut and bent, as will be presently explained.

Upon that side of the part A' of the frame nearest the shaft B' are provided adjustable ways K, having grooves in their adjacent 10 sides to receive a strip of metal L, from which the pieces which are to form the binders are cut. These ways are secured by screws, which pass through slots k, formed laterally at intervals therein, in order that they may 15 readily accommodate themselves to strips L of various widths.

The bending mechanism consists of a flat bar M, dovetailed within a groove a^3 , formed in the bed portion of the frame A and provided 20 with an upward projection m, a cam M', mounted on the counter-shaft B', which by contact with said projection m moves said bar the required distance to bend the piece of metal l, and a suitable spring m', connecting said bar with the machine-frame in a manner to cause the former to return after each movement occasioned by the said cam to its normal position.

The cutting mechanism consists of a bar 30 N, dovetailed within a groove formed for the purpose in the said bender M, and provided with an upward projection n, a cam N', mounted on the counter-shaft B', which by contact with said projection moves the cutter to its work, and a suitable spring n', connecting 35 said cutter with the machine-frame and adapted to return the former to its normal position after having cut off one of the pieces of metal l. A bed-guide or cutting-block P 40 has a cutting-edge p, against which the strip of metal L rests while the cutter is performing its work, and screws p' will secure the said block in its proper position. The under side of said block P is formed on an incline 45 from the said cutting-edge to its bottom, and the bed portion of the frame of the machine is formed on an opposite incline, thus forming an inclined passage Q, in which the pieces l become sufficiently bent by the bender to 50 enter their final resting-place R, formed between the disk C and either of the clamps F. The upper parts of each end of these clamps F are beveled, as shown, and the back side of the under portion of the presser-bar or 55 plunger J is likewise beveled, as at j, (seen in Fig. 3,) so that the downward movement of the latter first moves a clamp back sufficiently to uncover a piece l while resting, as seen in Fig. 10, upon the disk C, and then spends its 60 force upon the said piece or binder l.

A balance or belt pulley S is mounted upon the shaft B, from which motion and power are communicated to the mechanism hereinbefore described. It may be here mentioned 65 that the cam driving the cutter may be so

placed upon the counter-shaft B' and so formed as to cause the cutter to cut the metal L and rest in the position shown in Fig. 8, while the bender M passes forward and returns, when the metal L may again drop to 70 the position shown in Fig. 7.

The operation of the machine is very simple. As each piece of metal or binder l is cut from the strip L the bender M is caused to strike it in its center and force its way through 75 the passage Q and into the chamber R, where it lodges until the disk C is rotated one quarter of a revolution, or to a position directly underneath the presser-bar J, and while another binder l is being carried under the 80 other clamp F the boxes or other articles to be bound or fastened by the said binders are placed within the binder, then at the front of the machine, and the presser-bar J descends, driving the clamp back, as seen in Fig. 10, 85 and fastening the binder to the article, as desired. Each clamp F is pushed back in this manner successively by the presser-bar J, thus "setting" their opposite end in proper position to form the pocket or chamber R for 90 receiving the binder l. The movement of the disk C is intermittent, its motion being arrested when one of the clamps reaches a point opposite to the cutter and bender and the other directly underneath the presser- 95 bar. The reciprocal bender M also serves as a means for feeding the binders l to the intermittent rotative table or disk C and its automatically-adjustable clamps.

Having described my improvements, what 100 I claim as new is—

1. In a metal cutting and forming machine, the combination, with suitable cutting, bending, and binding mechanism, substantially as described, of an intermittently-rotative table 105 or disk and automatically-adjustable clamps mounted thereon, substantially for the purpose set forth.

2. The combination of an intermittently-rotative table or disk, two or more automatically-adjustable clamps mounted thereon, a reciprocal cutter, a reciprocal bender, their driving mechanism, and a presser-bar, all 110 substantially for the purpose described.

3. In a metal cutting and forming machine, 115 the combination, with a suitable supporting-frame, of an intermittently-rotative table or disk, two or more automatically-adjustable clamps mounted thereon, having their ends beveled, suitable cutting and bending mechanism, and a presser-bar having one edge beveled, all substantially for the purpose set forth.

In testimony whereof I affix my signature in presence of two witnesses.

JEREMIAH E. CHAPMAN.
